UNITED STATES PATENT OFFICE

THOMAS H. TISE, OF WINSTON-SALEM, NORTH CAROLINA

REINFORCED BEAM CONSTRUCTION

Application filed August 25, 1925. Serial No. 52,416.

This invention relates to reinforced concrete beams and particularly to constructions in which concrete and reinforcing members are placed in the channel between aligned 5 rows of blocks or tile to constitute the beam.

The invention will be described as applied to the construction of reinforced concrete floors. Although the end sections of the beams are subjected to negative bending moments, it is customary to employ the same 10 size and shape of tile throughout the length of the beams. My invention contemplates the use of differently shaped tiles or blocks at those sections which are subjected to negative 15 and to positive bending moments, respectively, the form for each section being so chosen as to make the most economical use of the materials employed.

Objects of the invention are to provide an 20 improved reinforced beam construction which will have a relatively high ratio of live to dead load, and one which may be made of reduced thickness for a given loading. A further object of the invention is to provide 25 a reinforced beam construction which may be readily and accurately built without necessitating the use of special block spacing apparatus and methods. More specifically, an object is to provide a floor beam having two 30 types of hollow blocks for giving the desired change in the cross-section of the beam and in the positioning of the reinforcing material.

An embodiment of my invention is illustrated in the accompanying drawings in 35 which:

Fig. 1 is a broken vertical section taken along the center line of a floor beam, the cement not being shown;

40 Fig. 2 is a plan of a portion of a floor, showing a completed beam and of two rows of tile assembled to receive the steel reinforcement and concrete;

Fig. 3 is a perspective view of a positive 45 unit block;

Fig. 4 is a perspective view of a positive and negative unit block;

Figs. 5 and 6 are, respectively, perspective 50 views of an intermediate and an end negative unit;

Fig. 7 is a broken vertical section on line 7—7 of Fig. 2; and

Fig. 8 is a view similar to Fig. 7 but illustrating blocks of a different size.

In the drawings, the blocks which are arranged at the sections of the beam subjected to positive and to negative bending moments are designated by the characters P and N, respectively, the concrete being identified by the character C and the reinforcing members by the character R. The general construction of floor beams embodying my invention is similar to known constructions in which the ends of the beams are rigid with the end support S and in which it is usual to employ reinforcing of such shape and location that two reinforcing rods lie at the bottom of the central section of the beam while the end sections have a rod at the top and another at the bottom of the beam.

The positive units P, that is the blocks positioned at the sections subjected to positive bending moment, are of approximately rectangular cross-section having a top wall 10 which is parallel to the bottom wall 11, lateral 75 flanges 12 preferably being provided as extensions of the bottom wall for automatically spacing the rows of tile apart and for closing the concrete receiving channel which is formed between adjacent rows. The side 80 walls 13 extend downwardly from and normal to the top wall for the greater part of the depth of the tile and are then contracted or recessed inwardly as at 14, to provide an increased channel width to take the two reinforcing members R. Lugs 15 extend outwardly from opposite sides of each block to provide a seat for the reinforcing members, the upper recessed surface 16 of the lug being spaced from the side wall and located 90 above the level of the bottom wall 11 and flange 12. Integral longitudinal fillets at the upper inner corners of the block provide lower surfaces 17 for the top wall, which 95 surfaces lie substantially parallel to a plane OA passing through the neutral axis of the beam and the outer upper edge of the computed compression area of the beam, this feature of the present invention being de- 100

scribed and claimed in my copending application Ser. No. 679,195, filed Dec. 7, 1923.

The negative units N are of the same height as the positive units and are provided with bottom walls 18 and lateral flanges 19 which are of the same width as corresponding elements of the positive blocks. The side walls 20 of the negative blocks extend upwardly from and normal to the bottom wall for the greater part of the height of the block, and then are contracted inwardly by inclined walls 21 which are preferably joined to the top wall 22 by short vertical walls 23. Seats for the lower reenforcement are provided by lugs 24 which project from the blocks and have downwardly inclined upper surfaces which lie above the level of the spacing flanges. The blocks at the extreme ends of the beam carry lugs 24' which are of greater height than the lugs on the other negative units, which lugs 24' provide a better bond by spacing the ends of the bars at a greater distance above the bottom of the concrete receiving channel.

The negative bending moment is a maximum at the extreme ends of the beams and the blocks N are provided with fillets 25 along their lower inner edges to assist in carrying the compression. Although the negative moments decrease towards the points of inflection, I prefer to incorporate the fillets in all of the negative blocks. The slope of the upper surface of the fillet 25 is such that it substantially coincides with the plane O'A' which passes through the neutral axis and the outer edge of the beam at the position of maximum negative bending moment.

The end blocks are provided with one end wall 26 for preventing the entrance of concrete into the blocks, the end wall being preferably indented from the end face of the block. The blocks of both sets are provided with a reenforcing rib 27 depending from the top wall of the blocks at their longitudinal center line and with a reenforcing flange 28 which projects inwardly from walls of the blocks. The blocks may be made by a molding operation, the flanges 28 and the reenforcement spacing lugs being made flush with one end of the blocks.

The blocks of adjacent rows are preferably arranged to break joint longitudinally of the beam, and the opposite walls at a point of inflection are formed by a positive and a negative unit, respectively. Considering one side of the beam, the positive unit blocks overlap one point of inflection and stop short of the other; the arrangement being reversed at the opposite side of the beam.

The rows of blocks may be quickly and accurately placed on the usual falsework as they are automatically spaced by the lateral flanges. The two different types of blocks are used as determined by location of the points of inflection of the beam and the cor-

rectness of the placing of the blocks of the respective type may be checked by inspection, since the top walls of the two types are of different width. With the rows properly laid, the steel bars are placed in the channels to rest upon the lugs which provide supports appropriate to the amount of steel at the base of the beam. Each lug 16 of a positive unit forms a rod-receiving seat, and the lugs 24, 24' of the opposite walls cooperate to form a single V-shaped seat at the central plane of the beam.

While the configuration of the outer surface of the blocks is dependent primarily upon the amount of space required for the reenforcement, the inner surface of the blocks is determined by the maximum positive and negative bending moments. Tile of different sizes are not, therefore, of identical design since the inclinations of the planes OA, O'A' which bound the compression areas vary with the depth of beam and maximum safe loading.

Figs. 1 to 7 inclusive illustrate ten inch blocks, while in Fig. 8, six inch blocks are illustrated. From a comparison of Figs. 7 and 8, it will be seen that the slopes of the surfaces of the fillets of both the positive and the negative units are smaller for the smaller size blocks.

The walls of the blocks not only act as the forms for the concrete of the beam but may be relied upon to take compression when a good grade of block is used and the blocks and concrete are placed with reasonable care. The central vertical portions of the walls are in longitudinal alignment from end to end of the beam, but the walls are recessed or indented inwardly to provide adequate space for the reenforcement where the latter is double. Due to the change in shape of the blocks, the rod seats and the rods at the points of inflection, any error in the placing of the blocks, or in the shape or location of the steel will be apparent when the reenforcing members are placed in the channel.

In addition to these advantages, a floor embodying my invention is characterized by relatively low dead weight, which lessened weight in the floor makes it possible to reduce the weight of the frame and footing of the buildings. As the dead weight is reduced, there is less material to buy, handle and place. For the same live load, the floor can be of less thickness, or for a given depth of floor and quantity of steel, higher live loads may be carried.

I claim:

1. In a reenforced concrete beam, two parallel rows of blocks, said rows being spaced apart to provide a channel between the opposed side walls of the blocks, and concrete and metal reenforcing in said channel, the vertical central portion of the side walls of all of the blocks in the respective rows being

in substantial alignment from end to end of the beam, the side walls of the blocks at the middle of the beam being contracted inwardly at the bases thereof and the side walls of the blocks at the end section of said beam being contracted inwardly at the top thereof.

2. In a reenforced concrete beam, two parallel rows of blocks, said rows being spaced apart to provide a channel between the opposed side walls of the blocks, and concrete and metal reenforcing in said channel, each of said blocks having top and bottom walls which are parallel to each other and are spaced apart by the depth of the beam, and having side wall portions which are substantially normal to said top and bottom walls, the blocks at the ends of the beam having inwardly sloping walls connecting the said side walls to the top walls thereof, and the blocks at the central section of the beam having inwardly sloping wall portions connecting the said side wall to the bottom walls thereof.

3. In a reenforced concrete beam having sections thereof subjected to positive and to negative bending moments respectively, two parallel rows of hollow blocks, means at the bottom walls of said blocks for maintaining the said walls of the blocks of the opposed rows in spaced relation to provide a channel therebetween, metal reenforcing members in said channel and concrete surrounding said members and filling the channel between said rows, the side walls of the blocks at the section subjected to a positive bending moment being recessed inwardly at the bottom thereof of adjacent said reenforcing members, and the side walls of the blocks at the section subjected to a negative bending moment being contracted inwardly at the top thereof adjacent said reenforcing members.

4. In a reenforced concrete beam having the ends thereof rigidly secured to spaced supports, parallel rows of blocks having side walls spaced apart to provide a channel, lateral flanges extending from the bottoms of the opposed rows of blocks to close the bottom of said channel, the blocks at the central portion of said beam having inwardly contracted portions at the base of the side walls and the blocks at the ends of the beam having side walls which contract inwardly at the top portions thereof.

5. In a reenforced concrete beam having sections thereof subjected respectively to positive and to negative bending moments, hollow blocks arranged in two parallel rows for defining a channel for the reception of concrete and reenforcing members, the blocks at the section subjected to a positive bending moment having top walls of substantially the same width as the bottom walls, side walls extending downwardly from and normal to said top wall and inwardly inclined walls joining the said side walls to the bottom walls,

the blocks at the section of the beam subjected to negative bending moment having side walls extending upwardly from and normal to the bottom walls thereof and inwardly inclined walls joining said side walls to the top walls thereof.

6. The invention as claimed in claim 3, wherein one side wall of the channel at a point of inflection is formed by one of the said blocks having side walls recessed at the bottom thereof, and the opposite side wall of the said channel is formed by one of the said blocks having inwardly contracted side walls.

7. In a reenforced concrete beam having end sections subject to negative bending moments and a central section subjected to positive bending moments, parallel rows of negative and positive unit blocks defining a channel for the reception of reenforcing metal and concrete, the negative unit blocks being located at the end sections and having side walls which provide an increased channel width at the top of the beam, and the positive unit blocks being located at the central section and having side walls which provide an increased channel width at the bottom of said beam, a negative and a positive unit block forming the opposed walls of the channel at a point of inflection.

8. In a reenforced beam having sections subjected to negative and to positive bending moments, respectively, parallel rows of blocks defining a concrete receiving channel of enlarged width at the top at the section subjected to negative bending moment and of enlarged width at the bottom at the section subjected to positive bending moment, lugs at the bottom of said channel for positioning the reenforcing members, the lugs at the section subjected to negative bending moment having upper surfaces sloping downwardly to the central plane of the beam and the lugs at the section subjected to positive bending moment having upper surfaces provided with concave recesses.

9. In a reenforced beam having sections subjected to negative and to positive bending moments, respectively, parallel rows of blocks defining a concrete receiving channel of enlarged width at the top at the section subjected to negative bending moment and of enlarged width at the bottom at the section subjected to positive bending moment, said blocks having laterally projecting lugs for positioning the reenforcing members and spacing the same above the bottom of the channel, the lugs formed on blocks at the section of negative bending moment having upper surfaces which slope downwardly to the central plane of the beam and the lugs formed on blocks at the section subjected to positive bending moment each having an upper surface provided with a recess at one side of the said vertical central plane.

10. In a reenforced concrete beam having sections subjected to negative bending moments at the end portions thereof and to positive bending moments at a central portion thereof, parallel rows of blocks providing a channel therebetween, and reenforcement-supporting lugs on the blocks, the lugs on the opposed blocks of adjacent rows at beam sections subject to positive bending moments each having an upper recessed surface defining a complete seat for a reenforcing member, and the lugs on opposed blocks at beam sections subject to negative bending members cooperating to define a single seat for receiving a reenforcing member, said last mentioned lugs each having a downwardly sloping upper surface.

11. The invention as claimed in claim 10, wherein the lugs on the extreme end blocks are of greater height than those of the intermediate blocks.

12. The invention as claimed in claim 5, wherein the lower surface of the top wall of the blocks at the section subjected to positive bending moment slopes downwardly from the center of the block to the side walls thereof, said surface being substantially parallel with a plane passing through the computed neutral axis of the beam and the outer upper edge of the computed compression area.

13. The invention as claimed in claim 5, wherein the upper surface at the outer edge of the bottom wall slopes upwardly towards the side walls, said surface being substantially parallel with a plane passing through the computed neutral axis of the beam and the lower outer edge of the computed compression area at the position of maximum negative bending moment.

45. In testimony whereof, I affix my signature.
THOMAS H. TISE.
